UNITED STATES PATENT OFFICE.

STILLMAN A. WEST, OF RACINE, WISCONSIN.

BURNISHING-MACHINE FOR BOOTS AND SHOES.

SPECIFICATION forming part of Letters Patent No. 288,532, dated November 13, 1883.

Application filed September 17, 1883. (No model.)

To all whom it may concern:

Be it known that I, STILLMAN A. WEST, of Racine, in the county of Racine, and in the State of Wisconsin, have invented certain new and useful Improvements in Burnishing-Machines for Boots, Shoes, &c.; and I do hereby declare that the following is a full, clear, and exact description thereof.

My invention relates to machines for burnishing the soles of shoes, and will be fully described hereinafter.

In the drawings, Figure 1 is a side elevation of my improved burnisher, and Figs. 2, 3, 4, 5, and 6 show in elevations and sections details of construction of same.

A is the burnisher-stand, with a counter, a' , in its circular base a , to firmly rest on top of a bench or table, in which it is secured by screws. Said stand A has the two box-bearings B B for the burnisher-shaft C, which has pulley D between said bearings, and is enlarged on its inside end, so as to form the head b . A slot, b' , is cut across the center of said head b for the flange a^2 , formed in the rear face of an eccentric bearing-plate, D', which has on its front face flange c , a socket, d , for the ball e of burnisher-spindle E', said ball e being held free to rotate in said socket d by locking-plate d' , screwed on top of said flange c . The eccentric bearing-plate D' may be adjusted on head b of shaft C, so as to vary the stroke of the burnisher, by means of two screws, e^2 e^3 , screwing in said head b through slots f f of said plate D'. The spindle or stem E' slides in the cylindrical burnisher shaft or holder E, which carries in its opposite end the stem E' of the burnisher F, which is held in said shaft by set-screw e' . In about the middle of its length said burnisher-shaft E is provided with a ring, e^2 , screwed on it, and which fits loosely in box-bearing (spherically hollowed) F' on front end of said stand A. A slot, h , is formed in said ring e^2 for the point of a pin, g , passing through said bearing F', and on which said burnisher-shaft E oscillates. G is the gas-pipe by which said burnisher may be heated. i is a hook suitably mounted in under face of stand to attach said pipe.

The pulley D of my burnisher being connected with the driving mechanism, the bur-

nishing-tool F has imparted an oscillating motion against any point of the sole presented to it. The operator, holding the shoe with both hands, can guide the sole against the face of the burnisher with the greatest ease, doing better work and more of it than when using a hand-burnisher.

Having thus described my invention, what I claim as new, and desire to secure by Letters Patent, is—

60

1. In combination with a burnisher for the soles of shoes, a drive-shaft provided with an adjustable eccentric bearing-head for the ball of the sliding stem of the cylindrical burnisher-shaft, whereby said burnisher is oscillated in a spherical bearing of said stand, substantially as set forth.

2. In a burnisher for the soles of shoes, the stand A, having box-bearings B B and F', in combination with the shaft C, having pulley D, head b , with slot b' , eccentric bearing-plate D', with flanges a^2 and c , socket d , and locking-plate d' , and burnisher having cylindrical shaft and sliding stem provided with ball e , substantially as shown and described, and for 75 the purpose set forth.

3. In a burnisher for the soles of shoes, the eccentric bearing-plate D', having flanges a^2 and c , socket d , and locking-plate d' , in combination with shaft E, having ring e^2 , with slot h for pin g , sliding stem E', with ball e , and stem E' for burnishing-tool F, substantially as shown and described, and for the purpose set forth.

4. In a burnisher for the soles of shoes, the 85 burnisher F and shaft or holder E, having ring e^2 , with slot h , in combination with spherical bearing F', having pin g , and mechanism, substantially as described, for operating the burnisher, substantially as described, and for 90 the purpose set forth.

In testimony that I claim the foregoing I have hereunto set my hand, on this 28th day of August, 1883, in the presence of two witnesses.

STILLMAN A. WEST.
